DRIVE CONTROLLING MECHANISM

John E. Peterson, Irvington, N. J., assignor to
 Van Vlaanderen Machine Company, Paterson,
 N. J., a corporation of New Jersey

Application April 8, 1932, Serial No. 603,943

13 Claims. (Cl. 242—55)

This invention relates to machines for handling a fabric or other flexible material (herein termed a "piece") by unwinding it from one beam and simultaneously winding it on another and then reversing the operation one or more times, as in the case of the dyeing machine known as a jigger in which in each pass the piece is passed through a dye liquor; I have illustrated the invention herein with respect to a dye jigger, and particularly one embodying the invention set forth in my preceding application filed December 31, 1931, Serial No. 584,090.

The principal objects are to effect the reversal automatically, while still preserving the mechanism subject to manual control so that if occasion requires the operation may be stopped at any time, and to provide settable means whereby the piece may be made to undergo any predetermined number of passes.

Fig. 1 shows one end elevation of a dye jigger embodying the invention;

Fig. 1a shows largely in section a differential forming part of the drive means for the beams of the machine;

Fig. 2 is a view looking toward the other end of the machine and showing the mechanism of the present invention in side elevation;

Fig. 3 is a partial end elevation of said mechanism;

Fig. 4 is a partial plan thereof, with parts in section on line 4—4 of Fig. 6;

Figs. 5 and 6 are sections on lines 5—5 and 6—6, of Fig. 4;

Fig. 7 is a view somewhat similar to Fig. 4 with the cover removed;

Fig. 8 is an elevation of the switch-controlling slide and the means whereby it is actuated, partly in section; and

Fig. 9 a view of certain parts shown in Fig. 6, being a section on line 9—9, Fig. 4.

In Fig. 1, 1 is the frame of the machine; 2 two parallel beams journaled therein and each adapted to be rotated in each direction; 3 reverse brake-straps, whereby when either beam is the delivering one the brake therefor is active and the other substantially inactive; 4 an electric motor having its shaft vertical and provided with a bevel pinion 5 and whose controller or switch 6 for controlling the current thereto, so as to drive the motor in either direction or stop it, is shown in Figs. 2, 3 and 5 (the wiring between the switch and motor being not shown); 7a the bevel gear portion of a rotary carrier 7 journaled in a housing 8, said portion 7a being geared with pinion 5 and said carrier having a bevel pinion 9

journaled therein on a radial axis; and 10 two shafts journaled in the carrier and having pinions 10a meshing with pinion 9 and worms 10b meshing with worm wheels 11 on the beam shafts, the parts 7a to 11 forming a differential drive from the motor shaft to the beams, whereby with the piece of fabric A wound on the two beams and such beams driven from the motor so as to wind up the piece on one beam while it is unwound or delivered from the other and with the latter subject to the resistance of its brake 3 the operation will proceed with the piece maintained in a state of tension between the two beams.

The beams at the end of the machine opposite to that shown by Fig. 1 (see Fig. 2) through worm 70 gearing 12 drive vertical shafts 13 journaled in the frame (one of the bearings therefor being shown at 32, Fig. 8, in a housing 13a) and these in turn through worm gearing 14 (Fig. 8) drive two controllers, here in the form of disks 15 journaled in the frame and each having adjustable with respect thereto, around its central stud, a tappet consisting of an arm 16 which may be clamped to the disk by a set-screw 16a and having a button 17. The disks and their arms form controllers 75 confined to move with the respective beams and adapted to control mechanism hereinafter described for reversing the motor.

Essentially, we have in the foregoing a reversible rotary system including the two beams on which the ends of the piece A to be treated are respectively wound and means (the motor) to rotate one beam and then the other in the direction to wind the piece thereon, said system also including the controllers respectively confined to 85 rotate with the beams and in a specific aspect of the invention forming actuators. (In a dyeing machine, as here illustrated by way of example, the piece A between the beams receives treatment by passing into dye-liquor in a vat 1z, Fig. 1.) 95

In brackets 18 projecting from the last-named end of the machine are pivoted two pawls or detents 19 which are normally held in the position shown by gravity but adapted to be retracted therefrom by the respective tappets, to wit, by 100 their buttons 17.

At the outset the piece stands wound on one of the beams 2; then, before it is passed to and wound up on the other beam with re-rotation of the first beam, the arm 16 corresponding to the 105 first beam is clamped to its disk 15 in the position where it will depress the adjoining detent or pawl 19, and when this winding has been effected and before winding back onto the first beam the tappet corresponding to the second beam is 110

clamped to its disk in the position where it will depress the corresponding pawl. Thereafter, in the passing of the piece back and forth between the two beams the tappet corresponding to the 5 delivering beam in each pass will move away from its detent and the other to its detent so as to retract it from its normal position.

Prefacing the description of the means shown by way of example for throwing the switch or controller 6 it may be generally stated that there is 10 means, as a rod, which is to be moved one way on the passage of the goods in one direction and then reversely on the reverse passage of the goods and which on each movement stores up spring 15 pressure in one or the other of two oppositely active springs so that the spring thus affected will be effective to throw one way or the other a shifting structure interposed between them and including such switch, it being understood that one 20 or the other of two detents is holding the shifting structure while the spring power is being thus stored up and that retraction of this detent (as from the beam which is about fully discharged of the goods) effects release of said structure and hence throwing of the switch. The rod or equivalent means, as will appear, may be moved in any 25 way in the proper direction on each pass of the goods, but preferably this is done automatically in the example.

30 A sliding member or slide comprising tubes 20, guided in the brackets 18, and a casting 21 forms with the motor controller or switch 6, with which it is disconnectively connected as will appear, the aforementioned shifting structure for reversing 35 the motor. The tubes are penetrated by a rod 22 having end heads 22a between each of which and casting 21 is a spring 23. Such rod and the springs form back-and-forth movable means to impose spring pressure on said structure, and if 40 the latter is held by the corresponding detent or pawl 19 against such movement power to move said structure in such direction will be stored up in the interposed spring, and if then the detent is retracted said structure will be shifted by the 45 spring in said direction. It is not essential that this means to impose spring pressure on said structure in this way be actuated automatically but I prefer so to actuate it thus, for instance as follows (see Figs. 4 and 6 to 9).

50 The casting 21 is hollowed out underneath (Fig. 8) and at that point the rod 22 has a pitman 24 pivotally connecting it with a crank 25 freely revolvable on one of the shafts 13 and having its hub (to which the lead-line for character 25 actually extends in Figs. 6 and 8) laterally prolonged (as seen by a comparison of Figs. 6 and 8) and formed with a top web 26 affording two opposite side faces 26a (Fig. 4) either of which may abut a wall 27a as the crank is turned one way or the 55 other to thus limit its rotation to 180°; said wall 27a is simply an upstanding flange (see Figs. 2, 4 and 6) at the back of an upwardly bulged portion of a cover plate 27 which is otherwise generally inclined forwardly and downwardly (Figs. 2 and 5) and is secured to the frame at 28 (Fig. 5), and whereas the web of the crank is arranged to impinge against wall 27a, as stated, the arm 25b of the crank, to which pitman 24 is connected, is below this wall, that is, movable underneath the 60 bulge as shown by dotted lines in Fig. 2 and also compare Fig. 6. Plate 27 has a rearwardly extending slot 27x (Fig. 4) to admit the crank when the plate is placed in position. Fast on the lower end of said shaft is a collar 29 having one or more 65 radial top cam-notches 29a adapted to receive a

pawl 30 which is spring-pressed downwardly and contained in the crank, 31 being the spring also contained therein. The lower bearing 32 for this shaft (contained in the corresponding or left hand housing 13a Figs. 2 and 8) is formed with a part-circular depending segmental projection 33 at the back thereof and of such circumferential extent that when the crank is moving from one of its mentioned limits to the other said projection will overlie the pawl 30, so that the latter is prevented from rising. Assume that the shaft, rotating in synchrony with the corresponding beam, is turning in the direction of the arrow in Fig. 6, the crank being at one of its limits against the wall 27a as shown in Fig. 4 and the pawl clicking idly over the notched top of collar 29, and next assume that the shaft starts to re-rotate; the pawl, falling into the first notch to approach, will pass under the projection, which will lock the pawl in the notch and thus the crank to the shaft, so that it re-rotates therewith. This latter will continue until the pawl clears the projection at its opposite side—the crank also reaching its other limit—, whereupon the shaft will continue rotating independently of the pawl. (The pivots at the 95 ends of the pitman and the axis of the crank-shaft 13 are alined when the crank is at either limit, so that the dead-center relation thus obtained maintains the tension stored up in the affected spring until the crank is shifted in the 100 way explained toward the other limit). Thus, each time a pass of the piece is completed and the return pass is begun the means including the pitman and crank becomes effective to store up tension in one or the other spring. 105

110 Assume that the piece is passing toward the left in Fig. 2 and that the right-hand detent or pawl 19 is holding the mentioned structure (including the slide and switch) in the left-hand position so that the motor is driving the beams 115 in the direction appropriate to such pass, the described means to impose spring pressure acting on said structure toward the right. When the piece has nearly unwound from the right-hand beam and consequently the adjoining controller 120 15—16 depresses said detent or pawl 19 said structure will be released and reverse the motor. Shafts 13 now starting to re-rotate the left-hand beam in the way described will cause the crank to reverse its position—or take the position of 125 Fig. 2—which will mean that said means will now exert spring pressure on said structure toward the left, and since the left-hand detent is now free of its controller 15—16 it opposes movement of 130 said structure so that the spring power becomes stored up for shifting of said structure to the left when the latter is next released by the left-hand detent. In short, when a pass in either direction is about finished release of said structure under tension of one spring is effected from 135 the train of parts 10—2—13—15 including the then delivering beam and when as a consequence reversal of the motor and two beams occurs and the pass in the opposite direction has begun the other spring is tensioned so as to be prepared to 140 shift said structure when that pass is about finished. In this way the machine might continue to reverse itself indefinitely.

145 (While the machine as herein shown and described in detail is adapted to reverse and, as it were, re-reverse, and so on, alternately, I do not wish to exclude a single reversing action.)

150 However the machine may be stopped at any time manually, as by disconnectively coupling the controller 6 with the slide so that the former may

be manually moved to the "off" position to stop the motor—that is, its mid-position. For this purpose let 34 be a control rod which is connected with the controller 6 by the gimbal joint 35 and 5 may slide in brackets 18 lengthwise and also rock therein and in the joint the same having two end handles 34a which by their weight hold a middle handle 34b with a roller 36 thereon normally engaged in a slot 21a of the slide. If this 10 control rod be depressed to clear the roller from said slot the slide and hence the controller can be shifted, independently of the slide, to the "off" position to stop the machine.

It is desired to stop the machine automatically 15 when some predetermined number (one or more) of passes have been effected, for which purpose when the last shift of the mentioned shifting or motor-reversing structure occurs it should be stopped part way of its normal stroke, so as to 20 leave the controller 6 at the "off" position. Hence a revoluble ratchet 37 is journaled in the cover-plate 27 and its journal stud 38 carries above the plate an elastic arm 39 equipped with a handle 40 and a pin 41 held by the elasticity of the arm 25 against the plate. In the circular path of the pin with the arm is a numbered series of recesses 42 in the plate all of which are mere rounded depressions with which the rounded end of the pin may have slip engagement excepting 30 that indicated 42a, which is a hole to receive the pin and form a positive stop for the ratchet. The casting 21 has two reversed pawls 43 spring-held against stops 44. When said reversing structure is at either limit one pawl is engaged 35 with the ratchet and the other spaced therefrom a distance corresponding to the spaces between the catching points formed at 42 and 42a (the normal range of movement of said structure being twice that distance), wherefore the first half 40 of the stroke of said structure in either direction to turn the ratchet is abortive. The ratchet is set with the arm at the catching point 4, for example. When it is shifted on the completion of the next to the last pass it will be positively 45 stopped at 42a and the then working pawl on the last pass will therefore come against the now checked ratchet, stopping the slide at the midpoint in its normal stroke. In other words, given the reversing structure movable to a definite position to reverse the motor and then back, and so 50 on repeatedly, there is means, on one of the strokes of said structure toward said position, to check the same short of said position comprising a ratchet arranged to be normally rotated through 55 a definite range by said structure, the fixed structure of the machine having a stop to check the ratchet and hence the reversing structure on said stroke of the latter; in the example, where the reversing structure is movable to either of 60 two positions in each of which it reverses the motor, said means is adapted to operate to check said structure short of either position, according to which of them it would otherwise approach.

Having thus fully described my invention what 65 I claim is:

1. A machine of the class described comprising a reversible rotary system including two beams on which the ends of the piece to be treated are respectively wound and means to rotate one beam 70 and then the other in the direction to wind the piece thereon and also including a controller confined to move with one beam, in combination with reversing means for the first means normally urged in the direction to reverse the latter and detent means normally restraining the reversing 75

means against such movement, one of said reversing and detent means being movable to clear the other and being controlled as to such movement by the controller.

2. A machine of the class described comprising 80 a reversible rotary system including two beams on which the ends of the pieces to be treated are respectively wound and means to rotate one beam and then the other in the direction to wind the piece thereon and also including a controller confined to move with one beam, in combination with a back-and-forth-movable reversing means for the first means normally urged in the direction to reverse the latter, detent means to restrain the reversing means against such movement, one of said reversing and detent means being movable to clear the other and being controlled as to such movement by the controller, and means to transmit motion from said system to the reversing means in the opposite direction 85

to engage the latter with the detent.

3. A machine of the class described comprising 90 a reversible rotary system including two beams on which the ends of the piece to be treated are respectively wound and means to rotate one beam and then the other in the direction to wind the piece thereon and also including an actuator confined to move with one beam, in combination with reversing means for the first means normally urged in the direction to reverse the latter, and 95 detent means normally restraining the reversing means against such movement, one of said reversing and detent means being movable to clear the other by the actuator.

4. A machine of the class described comprising 100 a reversible rotary system including two beams on which the ends of the piece to be treated are respectively wound and means to rotate one beam and then the other in the direction to wind the piece thereon and also including an actuator 105 confined to move with one beam and having an adjustable tappet, in combination with reversing means for the first means normally urged in the direction to reverse the latter, and detent means normally restraining the reversing means 110 against such movement, one of said reversing and detent means being movable to clear the other by the tappet.

5. A machine of the class described comprising 115 a reversible rotary system including two beams on which the ends of the piece to be treated are respectively wound and means to rotate one beam and then the other in the direction to wind the piece thereon and also including actuators confined to move with the respective beams, 120 reversing structure for said means shiftable back and forth, detents arranged one to oppose movement of said structure in one direction and the other to oppose such movement in the other direction, said detent and said structure, when the 125 former opposes movement of the latter, being one movable to clear the other by the actuator, and back-and-forth-movable means to impose spring pressure on and thereby urge said structure first in one and then in the other direction. 130

6. A machine of the class described comprising 135 a reversible rotary system including two beams on which the ends of the piece to be treated are respectively wound and means to rotate one beam and then the other in the direction to wind the piece thereon and also including actuators 140 confined to move with the respective beams and each having an adjustable tappet, reversing structure for said means shiftable back and forth, detents arranged one to oppose movement 145

150

- of said structure in one direction and the other to oppose such movement in the other direction, each detent and said structure, when the former opposes movement of the latter, being one movable to clear the other by the actuator, and back-and-forth-inmovable means to impose spring pressure on and thereby urge said structure first in one and then in the other direction. 80
7. A machine of the class described comprising two rotary trains respectively including beams on which the ends of the piece to be treated are respectively wound and means to rotate one train and then the other in the direction to wind the piece on the beam of such train and also respectively including actuators, reversing structure for said means shiftable back and forth, detents arranged one to oppose movement of said structure in one direction and the other to oppose such movement in the other direction, each detent and said structure, when the former opposes movement of the latter, being one movable to clear the other by the actuator, back-and-forth movable means to impose spring pressure on and thereby urge said structure first in one and then in the other direction, and means, actuated from one train, to move the last-named means in one direction on a release of said structure and then in the other direction on the next such release thereof, and so on, alternately. 90
8. A machine of the class described comprising a reversible rotary system including two beams on which the ends of the piece to be treated are respectively wound and means to rotate one beam and then the other in the direction to wind the piece thereon and also including actuators confined to move with the respective beams, reversing structure for said means movable back and forth and comprising a shiftable member and a reversing controller for said means disconnectedly connected and also movable back and forth together, detents arranged one to oppose movement of said structure in one direction and the other to oppose such movement in the other direction, each detent and said structure, when the former opposes movement of the latter, being one movable to clear the other by the actuator, and back-and-forth-movable means to impose spring pressure on and thereby urge said structure first in one and then in the other direction. 100
9. A machine of the class described comprising with supporting means, a reversible rotary system including two beams on which the ends of the piece to be treated are respectively wound and means to rotate one beam and then the other in the direction to wind the piece thereon, a reversing structure for the latter means movable to a definite position to reverse the same and then back, and so on repeatedly, and means, on one of the strokes of said structure toward said position, to check said structure short of said position comprising a ratchet arranged to be normally rotated through a definite range by said structure, the first means having a stop to check the ratchet and hence said structure on said stroke of the latter. 105
10. A machine of the class described comprising, with supporting means, a reversible rotary system including two beams on which the ends of the piece to be treated are respectively wound and means to rotate one beam and then the other in the direction to wind the piece thereon, a reversing structure for the latter means movable to either of two positions in each of which it reverses the latter means, and means, on one of the strokes of said structure from one position to the other, to check said structure short of the latter position comprising a ratchet arranged to be normally rotated through a definite range by said structure on each back and forth movement thereof, the first means having a stop to check the ratchet and hence said structure on said stroke of the latter. 110
11. In combination, supporting structure having a bearing, a back-and-forth revoluble element journaled in the bearing and having a surface spaced from and facing the bearing and formed with a cam-notch, means to be reciprocated, a crank revoluble on said element between the bearing and said surface and operatively connected with said means to reciprocate the same and having its rotary motion in each direction limited by said structure, said bearing having a projection extending toward said surface, and a pawl movable in the crank lengthwise of the axis of said element between the bearing and said surface and substantially equaling in extent the space between said projection and the bottom of the notch. 115
12. A machine of the class described comprising two rotary beams, a reversible motor, a differential drive connecting the two beams and driven by the motor, a movable controller, bearing for driving the controller from one beam at a relatively slower rate than such beam, and mechanism, controlled by the controller, for reversing the motor. 120
13. A machine of the class described comprising two rotary beams, a reversible motor, a differential drive connecting the two beams and driven by the motor, a movable controller having a tappet, gearing for driving the controller from one beam at a relatively slower rate than such beam, and mechanism, controlled by the tappet, for reversing the motor. 125

JOHN E. PETERSON.

CERTIFICATE OF CORRECTION.

Patent No. 1,966,081.

July 10, 1934.

JOHN E. PETERSON.

It is hereby certified that error appears in the printed specification of the above numbered patent requiring correction as follows: Page 4, line 120, claim 12, for "bearing" read gearing; and that the said Letters Patent should be read with this correction therein that the same may conform to the record of the case in the Patent Office.

Signed and sealed this 7th day of August, A. D. 1934.

Leslie Frazer

(Seal)

Acting Commissioner of Patents.
